THERMOSTATICALLY CONTROLLED LIQUID
FUEL FEEDING DEVICE

Roy W. Johnson, Milwaukee, Wis.

Application December 23, 1939, Serial No. 310,777

2 Claims. (Cl. 236—48)

This invention relates generally to a thermostatically controlled liquid fuel feeding device, and more particularly to a device of this character which is especially designed and adapted for controlling the operation of oil-burning water heaters.

One of the objects of the invention is to provide a control mechanism of this character, which insures a dependable oil flow, and the maintenance of a definite clean low fire and a full high fire, the possibility of an indefinite intermediate fire being precluded.

Another object of the invention is to provide a control mechanism of this character having these advantages, and which may be readily adjusted manually to maintain any desired water temperature over a wide range, for example over a temperature range of from 110° F. to 160° F.

A further object of the invention is to provide a control mechanism of the character referred to, and having the advantages and capacities mentioned, and which is so constituted as to make it practical to eliminate the costly pressure-tight thermo bulb well and replace it with a simplified bulb mounting and shield.

A further object of the invention is to provide a control mechanism operated by a vapor pressure responsive, expandible, collapsible diaphragm or bellows-type power element which will move the controlled device to its off or low fire position upon a failure in the power element.

A still further object of the invention is to provide in a control mechanism operated by a vapor pressure responsive, expandible, collapsible diaphragm or bellows-type power element a spring for compensating for the gradual increasing vapor pressure required to continue the expansion of the diaphragm or bellows after its initial distortion. Furthermore, the spring is arranged to compensate for this required increase in pressure without any substantial variation in the load imposed upon the spring.

In carrying out the present invention the control mechanism is preferably combined with a constant level control device, and the control mechanism itself is so constituted and organized as to effect opening and closing movements of its metering valve with a snap action to insure either a definite clean low fire or a full high fire. Any particular water temperature within the range of the control may be selected merely by manually adjusting or turning a temperature regulating knob which is conveniently mounted on the top of the control, and is, of course, accessible from the exterior thereof.

Other objects and advantages reside in certain novel features of the construction, arrangement, and combination of parts, which will be herein-after more fully described and particularly pointed out in the appended claims, reference being had to the accompanying drawings forming a part of this specification, and in which:

Figure 1 is a view in longitudinal central vertical cross section showing a thermostatically controlled liquid fuel feeding device embodying the present invention, parts being shown in elevation for the sake of illustration.

Figure 2 is a view in horizontal cross section taken on line 2—2 of Figure 1 and looking in the direction of the arrows.

Figure 3 is a plan view taken from line 3—3 of Figure 1 and looking in the direction of the arrows showing the device with cover removed.

Figure 4 is a fragmentary view in vertical cross section taken on line 4—4 of Figure 1.

Figure 5 is a similar view taken on line 5—5 of Figure 1.

Figure 6 is a view in elevation showing the control proper detached from the constant level device but equipped with its capillary tube and thermo bulb.

Figure 7 is a view partly in elevation and partly in cross section, illustrating a typical installation of the control device embodying the present invention on an oil-burning water heater.

Figures 8 and 9 are detail views in top plan of the valve-operating lever and thermostatically controlled actuated lever, respectively.

Figure 10 is a detail view in bottom plan of the adjusting lever; and

Figure 11 is a fragmentary view in transverse section taken on line 11—11 of Figure 2.

Referring to the drawings, and more particularly to Figure 1, it will be seen that the liquid fuel feeding device embodying the present invention, comprising a casing designated comprehensively at C and including a main casing 12 and a cover or control casing 13, is applied to the top of the main casing 12 and suitably or releasably interconnected therewith, as for example by a number of screws 14. A so-called constant level valve is provided in the main casing 12 and includes a float control inlet valve 15 and a safety cut-off mechanism designated generally at 16. These parts will not be described in detail as per se they form no part of the present invention and are fully described and claimed in United States Letters Patent 2,068,138, granted to Roy W. Johnson, January 19, 1937, for "Device

for controlling flow of fluid to oil burners and the like."

The casing 1 is provided with the usual outlet which is connected up to the burner in the usual way and flow through the outlet is regulated by metering valve 17 biased to open position by a spring and controlled as to position by the control device constituting the present invention.

The details of the valve construction also per 10 se form no part of the present invention but are fully described and claimed in my application for "Interchangeable metering valve control," filed June 23, 1938, Serial No. 215,336.

The control device, in which the present invention is embodied, comprises a valve-operating lever 20, which may be stamped from sheet metal (see Figures 1 and 8). At one end the lever 20 is provided along its side edges with apertured mounting ears 21. A pivot pin 22, supported by 15 lugs 23, cast integral with the control casing 13, extends through the aligned opening of the ears 22 to fulcrum or pivotally support the lever 20 at one end. At the end opposite its fulcrum the lever 20 has an offset valve engaging arm or portion 24, which is designed to bear against the upper end of the metering valve 17 so that when the lever 20 is swung in such manner that its arm 24 moves downwardly toward the valve 17, it moves the valve 17 to low or pilot fire position, whereas when the lever 20 is so moved that the arm 24 is swung away from the valve, the spring with which the metering valve is equipped moves the valve to high fire position. This valve-operating lever 20 is also provided with an offset and pointed projection 25 for a purpose which will hereinafter more clearly appear.

A thermostatically controlled actuating lever 26 is combined with the control and is shown in detail in Figure 9. This lever 26 is positioned in the control to underlie the valve-actuating lever 20. The lever 26 may also be stamped from sheet metal, and adjacent one end is provided with side flanges 27 having transversely aligned pivot openings 28 through which the pivot pin 22 also extends, this pivot pin providing a fulcrum for the lever 26 as well as for the lever 20. The flanges 27 of the lever 26 overlap the pivot ears 21 of the lever 20. Washers 29, mounted on the pivot pin 22, are interposed between the flanges 27 and the pivot pin supporting lugs 23.

The body of the lever 26 to one side of its fulcrum is provided with an upwardly displaced portion 30 centrally apertured as at 31 and having bearing seats 32 on its underside on the opposite sides of the aperture or opening 31. The opening 31 of the portion 30 of the lever 26 is axially aligned with a power element or bellows, designated generally at 35. This power element is releasably secured against an inwardly directed annular flange 36 integral with the top of the cover and provided at the lower end of a chamber 37 formed in the top of the cover to accommodate the power element. Screws 38 releasably fasten the power element in position. The power element includes a casing 39 and an expansible diaphragm 40 suitably combined and hermetically sealed to the casing. A short vertical shaft 41 has its upper end suitably attached to the center of the diaphragm 40, and its lower end extends down through the opening 31 in the lever 26. Below the lever 26 a plate-like collar 42 is assembled with the shaft 41 and is

held in position thereon by a nut 43. The collar is oblong in form, and at its ends has upwardly directed pointed projections 44 which engage the bearing seats 32 in the displaced portion 30 of the lever 26. This construction provides a driving connection or motion transmission train between the power element 35 and the actuating lever 26 of such a character that when the volatile fluid, with which the power element is partially charged, cools and the vapor pressure decreases, atmospheric pressure acting upon the diaphragm 40 will cause the shaft 41 to move upwardly, whereby the lever 26 will be swung in a clockwise direction as viewed in Figure 1. When its charge is heated up the vapor pressure increases and overcomes the force of atmosphere acting upon the diaphragm 40 causing the shaft 41 to move downwardly whereby the lever 26 will be rotated in a counter-clockwise fashion, as viewed in Figure 1 by the compression in the coil spring 58 hereinafter described.

Intermediate its ends the lever 26 is provided with a longitudinal slot 45, which underlies the projection 25 of the valve-operating lever 20, and also extends to one side thereof. At one end of the slot a pointed and offset projection 46 is provided, and is longitudinally aligned with the projection 25 of the valve-operating lever. Spring cups 47 and 48 are engaged with the projections 25 and 46, respectively, and have their body portions suitably socketed or seated for this purpose. The flanges of the cups 47 and 48 embrace a compression coil spring 49 interposed between and confined by the cups. One end of the lever 26 is formed with a second pointed projection 50 which is disposed in cooperative relation to a cooperable pointed projection 51, which is fixedly or adjustably mounted on the control casing. For this purpose the projection 51 may have the portion of its shank threaded, as at 52, and interengaged with the threaded hole in the wall of the casing that may be secured in adjusted position by means of a nut 53. Spring cups 54 and 55 are engaged with the projections 50 and 51, respectively, and receive and confine the ends of the compression coil compensating spring 56.

The projection 51 is so positioned relative to the pivot pin 22 and the arc of travel of pointed projection 50, that the line passing between the points 50 and 51 never passes above the axis of pivot pin 22. Thus, spring 56 continually urges lever 26 in a clockwise direction. As the pointed projection 50 moves upwardly upon the counter-clockwise motion of the lever 26, the moment of force exerted by the coiled compression spring 56, tending to cause the lever 26 to move in a clockwise rotation, rapidly decreases. This is due to the rapid decrease in the length of its effective lever arm with respect to pivot pin 22. The arc of the travel of pointed projection 50 is very short and as it is about the center of pivot pin 22 positioned a substantial distance therefrom the point of projection 50 moves through substantially a straight line. Hence, there is little compressing or stretching of spring 56, its compensation being accomplished through the change of the moment of force exerted by it as its axis of action rotates about the fixed projection 51. As the distance between projections 50 and 51 is decreased by the manual adjustment of projection 51, the greater will be the swing of 70 the axis of spring 56 for the same angular move-

ment of lever 26. This provides a sharp adjustment without undue change in the stress of spring 58. The distance between points 59 and 61 is short as compared to the distance between point 51 and pivot 22. This proportion results in making the device sufficiently sensitive for use with vapor pressure power elements.

The end of the lever 26 opposite its projection 58 is fashioned to provide a spring seat 57 in which one end of a coil spring 58 is engaged, and the opposite end of the coil spring 58 is interengaged with the spring seat 59 provided on an adjusting lever 60. The adjusting lever 60 has the end thereof opposite its seat 59 fulcrumed on a pivot pin 61 suitably supported by the control casing. The lever 60 may be moved to vary the compression of coil spring 58 by virtue of the provision of an adjusting regulating knob 62, which is fixed to the upper end of the adjusting screw 63. The adjusting screw 63 has the threaded portion 64 of a shank interengaged with the threaded bearing 65 provided in the top of the control casing. The lower end of the screw 63 bears down against the lever 60. As the knob 62 is turned in one direction the screw 63 is fed downwardly and depresses the lever 60 to increase the compression of the coil spring 58. Reverse turning of the screw 63 decreases compression of the spring 58. The compression in spring 58 acts against the force of atmosphere against the diaphragm 40 and continually urges it to expand. The spring 58 thus continually tends to move the lever arm 26 in a counterclockwise direction, which effects the movement of the control valve to its low fire position, as hereinbefore explained. Hence, if there is a failure or leakage in the bellows 35, so that atmospheric pressure exists on both sides of the diaphragm 40, the spring 58, having sufficient force, will move the control device to the low fire position and hence constitute a fail-safe feature.

High and low fire stops are provided and contact with the arm 24 of the valve-operating lever 20 to determine the high and low fire position of the metering valve. The low fire stop, which is designated at 66, may be in the form of an inverted screw having its shank 67 interthreaded with an adjusting sleeve 68 threadedly interconnected with the top of the control casing. The head 69 of the screw of the low fire stop is at its lower end, and is in the path of the swing of the arm 24 of the valve-operating lever. A nut 70 and spring 71 releasably secure the low fire stop in any selected adjustment.

Two high fire stops, designated at 72 and 73, are provided. One of these high fire stops, namely the stop 73, is factory adjusted, and may be secured in place by a drop of solder, or the like, so as to provide a fool-proof maximum adjustment. The fire stop 72 may be adjusted in the field. Both of these fire stops are in the form of screws threadedly connected with the casing and releasably retained in adjustment by means of spring 74 and nut 75. The lower ends of both screws overlie and are engageable with the arm 24 of the valve-operating lever. The bellows or pilot element 35 is connected to one end of the capillary tube 80, and at the other end of the tube a thermo bulb 81 is provided. An adjustable stop 73a has its inner end positioned to engage with the upper surface of the outer end of lever arm 26 to limit the counterclockwise motion thereof.

In installing the control embodying the present invention on a water heater, as for example on an oil-burning water heater of the type shown in Figure 5, a portion of the insulating jacket 86 is cut away as at 87, and the thermo bulb 81 is placed against the metal wall 88 of the heater, and is held in place by means of a cover plate 89 releasably fastened to the jacket and covering the opening or recess 87.

As viewed in Figure 1, the parts are shown in high fire position with the lever 26 urged against its stop 72 by the spring 49. The temperature at which the control will move to low fire position is predetermined by the adjustment of regulating knob 62. The greater the compression of spring 58 the lower that temperature point will be. As the temperature of the water in the tank 25 increases, vapor pressure increases to cause a downward movement of the shaft 41. The consequent stretching of the diaphragm 40 is aided by the force compressed into spring 58 by the regulating of knob 62. The downward movement of shaft 41 permits lever 26 to move counterclockwise and decreases the moment of force with which spring 58 resists such counterclockwise movement. With each increment of increase in vapor pressure, there will be increasingly large increments of stretch resistance in the diaphragm 40. At the same time the effective aid of coil spring 58 is slightly decreased, due to its expansion and consequent loss of some of its potential energy. However, the increasing force, required to effect further increments of movement of the lever 26 in a counterclockwise direction, is directly compensated for and balanced by the decreasing moment of force of compensating spring 56.

When the predetermined temperature of the water in the tank has been reached the lever 26 will have carried its pointed projection 46 above the line between the point 28 on valve-operating lever 20 (now in its high fire or upper position) and the pivot 22 and the valve-operating lever 20 will be moved clockwise with a snap action to its low fire position. As the bellows 35 expands in the movement to low fire position, and as the bellows 35 is operated under an internal pressure normally lower than atmosphere, if a leak occurs in the bellows, atmospheric pressure is permitted to enter and equalize the pressure on both sides of the diaphragm 40. The force of the spring 58 will then move the control to its low firing position. Hence, a fail-safe action occurs. This is particularly important in controlling gravity feed oil burners.

As the temperature in the water tank decreases from the predetermined high, the vapor pressure in the bellows 35 decreases. The bellows starts to gradually collapse due to the effect of atmospheric pressure operating on the outside of diaphragm 40. Such gradual collapse of the bellows unstresses diaphragm 40 and it inherently exerts less force in aiding the collapse. The collapse of the bellows 35 also compresses spring 58. The force required to compress spring 58 increases with each increment of collapse of the bellows and compression of that spring. However, the collapse of bellows 35 directly causes a clockwise movement of the lever arm 26. This clockwise movement is aided by the moment of force in compensating spring 56. This moment of force increases with each increment of clockwise movement of lever 26 and hence compensates for the loss of stressed tension in dia-

phragm 40 and the increased compressive force in spring 58. Hence, both the force changes, due to the collapsing and expanding of the bellows, and the compression and expansion of spring 58, are variably balanced by the compensating spring 66, and the ultimate movement of the metering valve is controlled accurately and entirely by the change in vapor pressure due to change in degree of temperature. The effect is to make the device operate within a closer range 10 of high and low temperatures.

The net results of this structural organization is that a more sensitive control element is provided, one which operates on a smaller temperature differential, and one which insures a definite, clean, low fire and a full high fire.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claims.

I claim:

1. In a control device for mechanisms having a high position and a low position, a pivoted actuating lever having limited movement in one direction to cause said mechanism to assume its high position and limited movement in the opposite direction to cause said mechanism to assume its low position, a spring acting upon said lever to constantly urge it in the low direction, a vapor pressure responsive, expansible, collapsible power element operatively associated with said lever to positively move said lever in the high direction as said power element collapses, said lever being moved in the low direction by said spring gas said power element expands, said lever having a fulcrum thereon movable through an arc of limited length as said lever moves from low position to high position, a relatively fixed

spring fulcrum opposed to said first mentioned fulcrum and positioned adjacent to the free outer end of said lever at a distance from said lever pivot appreciably greater than is said first mentioned spring fulcrum and beyond the limit of pivotal movement of said lever in said low direction, and a compensating compression spring pivotally mounted on said opposed fulcras to continually urge said lever in said high direction whereby the relative movement of said fulcras effects substantial changes in the turning moment exerted upon said lever by said compensating spring.

2. In a control device, a pivoted actuating lever for limited pivotal movement, an adjustable compression spring acting upon said lever to urge it to move in one direction, a vapor pressure responsive, expansible, collapsible power element acting when collapsed to urge said lever 15 to move in the opposite direction, a compensating spring continually urging said lever in said opposite direction, said spring being pivotally supported by and between a fulcrum point on said lever and a fulcrum point relatively fixed with 20 respect to the pivot point of said lever, the distance between said fulcrum points being short with respect to the distance between said relatively fixed fulcrum point and the pivot of said lever, said fixed fulcrum point being disposed so 25 that a line between it and the pivot of said lever falls outside of the range of movement of said lever but close to the limit of movement thereof in the direction in which it is moved by said compression spring, said relatively fixed fulcrum 30 point being manually adjustable toward and from the fulcrum point on the lever to vary the distance between said points whereby the variation in turning moment exerted on said lever by said compensating spring may be increased 35 or decreased while maintaining a substantially uniform load on the spring for any position of adjustment of said fixed fulcrum point.

ROY W. JOHNSON.
